CLAIM

The ornamental design for a caddy for beverages, tools
or the like for a lawn mower handle, as shown.

DESCRIPTION

FIG. 1 is a top plan view of a caddy for beverages, tools
or the like for a lawn mower handle showing my new
design.

FIG. 2 is a bottom plan view thereof.

FIG. 3 is a front or rear elevational view thereof.

FIG. 4 is a left or right side elevational view thereof.
